COKING RETORT OVEN

Joseph van Ackeren, Pittsburgh, Pa., assignor to
Koppers Company, a corporation of Delaware

Application May 14, 1936, Serial No. 79,669

14 Claims. (Cl. 202—143)

This invention comprehends improvements of general utility in the coking retort oven art; and comprehends more specifically improvements in the means for delivering the underfiring media into the combustion flues of coking retort oven underfiring systems and more especially pertains to the means for controlling and regulating the volumes of said underfiring gases delivered from the regenerators into the flame flues. The instant invention is especially applicable to coking retort ovens provided with vertically disposed heating flues having regenerators beneath, and its advantages will be realized either in combination ovens or in ovens equipped only to be underfired with rich gas. A principal advantage provided by my present improvement resides in its furnishing means for bringing different commercially used underfiring gases into contact with the combustion air, in the underfiring system, in a manner recognizing the differences in their individual combustion characteristics, and consequently provides means for promoting a more efficient and uniform distribution of the heat liberated by the burning gases to the retort heating walls. As specific examples of the type of coking retort ovens in which the present improvement finds special application, the well-known cross-over cross-regenerative type ovens exemplified in the patent to Joseph Becker No. 1,904,191 dated April 18, 1933, and his prior Patent No. 1,374,546 dated April 12, 1921, are cited, and also his application S/N. 2,564 filed January 19, 1935.

In commercial installations for the carbonization of coal, the carbonization process is promoted by burning either rich or lean fuel gases, that is, gases of relatively high or low calorific value respectively, in the combustion flues of the coking structure. Rich gas, such as is formed and evolved during the carbonization process, may be returned in part to the underfiring system and there burned to further promote the distillation of the coal charge. A lean gas of lower thermal content and produced extraneously of the carbonization system, as for example producer and blast furnace gases, is also used for the same purpose. The rate of flame propagation in rich gas is so rapid that numerous means and devices have been especially developed to the end of retarding its burning rate and avoiding too localized an evolution of the heat resulting from its combustion. In the leaner gases, as for example the above-mentioned, the flame propagates relatively slowly, so much so, that for their effective and efficient employment in the underfiring of a coke oven battery, a pre-

heating step is necessary for their satisfactory use. The progress of the lean gas combustion reaction, even after preheating, is still comparatively slow and the evolution of much heat relatively tardy in developing after admixture with the combustion air. 5

In combination ovens which are designed and equipped to be heated optionally by either rich or lean gas, the coke-oven designer is confronted with the problem of providing an underfiring system which will equally effectively employ either a highly combustible rich gas or a lean gas to heat the same ovens and coke the coal charge uniformly. In consequence of the above-mentioned distinctions between the combustion of gases of 15 high and low calorific value, it is apparent that the rich gases have a tendency to burn too rapidly in the lower zones of the heating flues and give rise to temperatures at that point that are higher than preferred. In the case of lean gas 20 underfiring, the contrary condition exists, i. e. the slower evolution of its heat content during combustion, tends to give rise to the phenomenon called "cool bottoms". An additional complication to the uniform heating of an oven charge is 25 provided by the fact that the pusher-side of an oven contains less coal than the coke-side, in consequence of which fact, more of the underfiring fuel gas must be burned on the coke side 30 than on the pusher side in order that the coking process will uniformly progress through the coal mass in any particular oven and all parts of said charge be ready to be discharged from the oven simultaneously. 35

From these facts, it becomes obvious, therefore, that a standard or permanent setting of the gas control means is difficult to establish and more especially so in a combination battery, and that, consequently, gas flow regulatory means are 40 of necessity provided within the battery structure if a uniform coking of the oven charges is to be effected under all conditions of operation. Such means should be easily reached and adjusted from the exterior of the battery and must 45 adequately provide for the above-mentioned dissimilarities to the end that uniform coking conditions are maintained at all points of the coking chamber walls. The regulatory devices used for this purpose are generally found at the bottoms 50 of the flame flues and adjacent to or within the ports through which the fuel gases and the air for their combustion are discharged into the flame flues from the ducts and conduits provided within the battery structure for their distribu- 55

tion into the combustion flues along the heating walls.

Among the objects of my present invention is the provision of an improved design for those ducts at the lower parts of the vertically extending heating flues of regenerative ovens through which the combustion air in the case of rich gas underfired ovens, and the combustion air and the lean gas in combination ovens, are introduced into the flame flues from the underlying regenerators. The improved duct of my invention and the orifice through which it ports into the flame flues is designed to supply to the up-burning flame flues, a vertically rising and freely flowing column of gases from adjacent regenerators feeding the same heating flues, and to provide means for regulating the volume of gases flowing from said orifices, which will neither provide interruptions in the flow-path of the 5 charged gases nor engender, at the mouth thereof, turbulence, eddies or other distortions within the gas stream, which will tend to divert the flow-path of the discharged gases from a normally vertically directed gas stream-path. The lean 10 gas and air conduit of my invention is constructed to deliver the underfiring air to the flame flues in the above-described manner, so as to provide within the heating flues of the ovens of a combination battery when they are operating as "coke" ovens, that is to say during those intervals underfiring is being effected with rich 15 gas, vertically directed and vertically rising air streams or currents, adjacent the columns of rich gas issuing from the rich gas nozzles, so that the columns of air and rich gas, upon entering the heating flues, will be free of any abnormal tendency to deviate from a vertical flow-direction. The mixing of the combustible gases provided 20 with such individual flow-paths progresses gradually at their margins of contact and a tendency 25 is thereby provided to somewhat retard the progress of combustion and to increase the interval required for that reaction to reach its end-point, or until a uniform commingling of the gases 30 within a heating flue is attained. The result is 35 to produce a more gradual evolution of heat along the walls of a coking chamber than in those instances where the flow-paths of the underfiring gases are such as to produce a more rapid diffusion of the combustive gases in the lower part of 40 the heating flues. The end result is a lengthening 45 of the flames in the up-burning flame flues.

When underfiring with producer or blast furnace gases, it is highly desirable to promote an effect in the heating flues quite opposite that 50 above-described. In consequence of the facts that immediately after their mixing, lean gases and air do not produce temperatures as high as can be effected with rich gas, and that the heating flues terminate in their lower part at the 55 same horizontal levels as the oven soles, it becomes obvious that initially mixing the underfiring air and lean gas at points too close to the bottoms of the heating flues, may give rise, in the coking chambers, to zones, having somewhat 60 lower temperature levels than preferred, at points adjacent the air and gas ports. Such situation 65 will effect the coking of the upper part of an oven charge before the lower, with the result that the coking time must be increased to fully carbonize the lower portion of the oven charge and prevent that portion thereof being under-cooked when pushed.

A further object of my invention is, therefore, 70 to provide simple and practical means for mix-

ing the lean gas and air flowing from their respective regenerators before they are introduced into the oven flame flues; and, as a further feature thereof, to provide said means with adjustable regulation which will permit not only regulation of the volumes of gases introduced into the combustion flues, but also to allow adjustment of the level, below the air and gas port, at which these underfiring media are first allowed to come in contact as they flow from the regenerators 10 into the combustion flues.

A further object of my invention is to provide a common air and lean gas port, at the lower end of the combustion flues of a coking retort battery, having such design and conformation that the 15 afore-delineated objectives will be effectively and simply realized, and furthermore will be of such disposition in respect of the gas conduits leading from the two regenerators communicating with each heating flue, that the volumes 20 of the gas flowing from each regenerator will be adjustable by means of a single and easily exchangeable flow-regulating device, supported within said port in such manner that its seat is adequately protected from the accumulation of 25 such adventitious material as may be present in the underfiring gases, and which at the temperatures existing within the flues would tend to flux with the refractory material thereof causing it to "freeze" and consequently interfere with its facile 30 removal or exchange.

The invention has for further objects such other improvements and such other operative advantages or results as may be found to obtain in the processes or apparatus hereinafter described or claimed.

According to the present invention, I provide below the lower part of each flame flue of a coking retort battery, a single vertically disposed and cylindrically-shaped duct that is substantially circular in horizontal cross-sectional area and is communicably connected at its lower end with the conduits that distribute gases from those regenerators with which each flue of a coking retort structure is in communication, and which 40 at its upper end ports into the lower part of the heating flues. Concentrically within each such cylindrically-shaped duct I support a cylindrically-shaped plug having a horizontal cross-section similar to that of the conduit, but of lesser 45 diameter. By diminishing or increasing the diameter of this plug, the free space, in the ring-shaped space remaining for the flow of gases from the regenerators, can be respectively increased or diminished.

In the accompanying drawings, forming a part of this specification and showing for purposes of exemplification, a preferred form and manner in which the invention may be embodied and practised, but without limiting the claimed invention to such illustrative instance or instances:

Figure 1 is a composite vertical section taken crosswise of a coke oven battery embodying features above specified and equipped with the improvements of the present invention, the figure 65 showing at the left a section through the battery heating walls, and at the right, a section through an adjacent coking chamber, said sections being taken along the lines A—A and B—B of Figure 2 respectively.

In the embodiment illustrated in the drawings, the invention is incorporated in a combination coke oven battery, that is, a battery having provision for being fired alternatively with an extraneously derived relatively lean gas, such as producer gas or with a relatively rich gas such as coke oven gas. For convenience, the present description will be confined to the present illustrated embodiment of the invention in such a combination oven battery; features of the invention may be applied to other structure, for example, to ordinary so-called "coke-ovens" fired with coke oven gas, or ordinary so-called "gas-ovens" fired with producer gas; hence, the invention is not confined in its scope to the combination oven or the specific use and specific embodiment herein described as an illustrative example.

The present improvements are useful with various types of coke ovens, and although the present embodiment, illustrated for purposes of exposition, is the well-known Becker cross-over type of oven battery, these improvements lend themselves to useful embodiment in a wide range of coke oven types and more especially in that class of ovens having their heating flues vertically dis-

posed in the heating walls thereof, and whether or not they are intended to function as "coke" or "gas" ovens.

The coking retort oven battery comprises a plurality of horizontally elongated coking chambers 5 10 in alternate side-by-side disposition with heating walls 12 therefor, and a plurality of side-by-side cross-regenerators 13, 14, beneath and extending substantially parallel with the plurality of coking chambers and heating walls. The regenerators are disposed in pairs along the lengthwise dimension of the battery, the pairs of co-operating regenerators being isolated by the oven supporting walls 15, and the individual regenerators of said co-operating pairs are separated by 15 the capital walls 16. In the capitals of the walls 16, the conduits 17, 18, are provided for flowing, into the flame flues 19, such of the underfiring media as are introduced into the sole-channels 20, 21, from flow-boxes provided therefor (and 20 not shown), said gases being distributed, by the sole-channel ducts 22, over the checker-bricks of the regenerative spaces for pre-heating them to a preferred temperature before they succeed to the flame flues through the conduits 17, 18. 25 These conduits converge as they extend upward, and meet at a point below the bottom of their respective flame flues, so that the gases flowing from the respective regenerators are provided with an opportunity to commingle before entering the flame flues through the ducts 23.

The heating walls of the battery comprise vertical heating flues 19 wherein the combustive underfiring media are burned, and the so liberated heat is absorbed by the refractory materials of 35 the oven chamber heating walls 12 and conducted to the coal charge previously introduced into the adjacent oven through the charging holes 24. The ends of the coking chambers are closed during the coking period by the doors 25, which function not only to retain the charged coal mass within the oven but also act to prevent the escape, into the atmosphere, of the volatilized distillation products. The gases, tar, etc., evolved, during the carbonization process, are drawn through 45 the ascension pipe 26 by an exhauster and assembled in a collecting main (not shown), from which they are flowed to various preferred treating steps for the segregation and recovery of valuable components.

The heating flues 19 of the heating walls are 50 separated from each other by the walls 27, and the flues comprising each heating wall are divided into sets of flues that are isolated from each other, for underfiring gas flow purposes, by the partition walls 35. In mutually adjacent heating 55 walls, the heating flues are arranged into corresponding groups, and the individual flues of any one such wall group are disposed to communicate at their upper ends with a horizontal bus channel 28 provided with an individual cross-over 29, centrally disposed of said bus channel, for carrying the products of combustion that assemble 60 therein upward and over the top of the adjacent oven and downward into a corresponding set of flues in the opposite heating wall. The similar and similarly positioned sets of heating flues in adjacent heating walls are interconnected in this manner by cross-overs extending over the tops of alternate coking retort ovens along the 65 battery.

All the heating flues of any one heating wall, crosswise of the battery, burn simultaneously and the combustive media, introduced into the lower part of an up-burning set of flame flues, rise therethrough to enter the horizontal channel 28 70

75

and flow over to a corresponding horizontal channel and set of flame flues in the opposite heating wall communicably connected therewith by cross-over 29, and at such times as the flow of gases is reversed in the regenerative system, the up-burning set of flues becomes the down-flowing set and vice versa.

For the purposes of convenience and exposition, I have embodied the features of my present invention in a coking retort battery structure having a heating flue disposition similar to that disclosed in the co-pending application S/N. 2,564 of Joseph Becker filed January 19, 1935. In that disclosure, the heating flues in each heating wall are disposed in groups of four heating flues each, except at each end of each wall where the end groups are in pairs, the several heating flues in each group being separated from each other by the vertical partitions 27 transverse of the heating wall, the partitions within each group stopping somewhat short of the top of the heating wall to provide the horizontal bus channels 28.

The gas flow from or to the heating flues traverses directly the cross-over conduit 29 positioned above the middle partition 27 of its group, and the tops of the alternate heating flue partition walls of each heating wall are flared, at 30, beneath the adjacent cross-over for each flue group to promote equality of gas flow to or from the heating flues of the same group irrespective of their distance from said cross-over. The gas flow regulating means situated at the lower part of the flame flues, for regulating the preferred volume flow of combustion media to the flues, are accessible through the inspection holes 36 extending to the top of the battery. It will be observed that no sliding brick are provided at the top of the flame flues for regulating the flow of gases into the cross-overs. In this embodiment of the invention, such regulation is effected at the bottom of the flues so that no impedance to gas flow is created within the flues, and the pressure at which the combustive gases are maintained therein is significantly reduced, with the result that the pressure differential between the flues and the coking chambers is small, and the opportunities for transfer of gases there-between materially reduced, as also set forth in the Becker application S/N. 2,564 supra.

At such times as the battery is operated as a "coke" oven and the heating gas used is of the higher calorific values, such as is produced by the coal distillation process and for its satisfactory combustion does not need regenerative pre-heating, it is introduced into the horizontal channels 31 located in the capitals of the regenerator division walls 16, and is distributed to the individual flues of the sets of flues comprising the heating walls through vertical conduits 32, individual for each flue, the same being provided with nozzles 34 whose orifices are graduated from one side of the battery to the other so that the variations in the static pressure of the gas at different points along said channels and the changes in the density of the gas effected as it flows through the hot region in which such channels are located, may be compensated for to the end that the preferred quantities of gas will be delivered to each flue from that channel.

The regenerators are disposed to operate in groups of four, each pair of which communicates for gas flow with those heating flues immediately above, and which are interconnected by common cross-over conduits. The two middle regenerators 14, 14 in each such group are air regenerators,

and the exterior regenerators 13, 13 of the group are disposed to carry heating gas when the battery is underfired with lean gas, but are disposed to preheat air when the underfiring is effected with rich gas. At such times as the ovens are operating as "gas" ovens, the regenerators 14, 14 are adapted for preheating air and during each period of the regenerative heating cycle when the flow of gas in the interconnected heating flues is reversed and the burning flame flues become the down-flowing flues and those regenerators that were formerly heating the combustive media are now carrying away combustion products and vice versa, an air regenerator is always interposed between a gas regenerator and those regenerators flowing the combustion products to the waste heat tunnel and the stack, thereby obviating the possibility of heating gas leaking into the down-flowing regenerators and fluxing the checker-bricks. The regenerators are so disposed for underfiring with lean gas that, at any given time, the alternate ovens of those ovens having no cross-over ducts passing over the tops thereof, are all being heated by combustion products flowing in the same direction through both of their adjacent heating walls; and in alternate groups of regenerators, each group of which comprises the four regenerators located beneath interconnected heating walls, the similar and similarly positioned regenerators are operating to carry the same kind of gases while the intermediate groups of regenerators are being supplied with gases in the reverse regenerator sequence, that is to say, in each group of regenerators the disposition of gases is respectively, at any instant, the mirror image of that in corresponding regenerators of adjacent groups thereof.

The regenerators are in two series lengthwise of the battery, one series for the pusher-side half of the battery, the cross regenerators of the one series abutting end for end, along the lengthwise middle of the battery, with the corresponding cross-regenerators of the other series and being separated therefrom by the median longitudinal partition wall 37.

As herein-above mentioned, each heating flue of the heating walls of the battery is communicably connected by an individual conduit with each of a pair of regenerators lying directly beneath each wall. According to my present invention, the pair of conduits 17, 18 for each flue are so disposed as to converge as they approach the bottom of the flues from the tops of the regenerators, and to meet in a common duct 23 at their upper ends. This duct is substantially cylindrical in shape, and its walls are substantially vertically disposed. The division wall 38, which separates the two adjacent conduits 17, 18 for each flue, terminates at a point below the duct 23, so that the gases flowing from the respective conduits are provided with opportunity to commingle before entering said duct to flow into the heating flue. The finial of the division wall 38 is formed at its center to provide a socket 39 whose upper edges lie in a horizontal surface. For regulating the volume of gases entering the heating flue associated with each duct 23, I provide the cylindrically shaped plug 40 provided at one end with a lug 41 formed to conform to and be received by the socket 39, wherein it is removably supported in a vertical position by the horizontal surface surrounding said socket. An increase or decrease in the cross-sectional area of the plug 40 respectively decreases or increases the area of the annular free space between the wall of the

duct and the plug to correspondingly reduce or improve the facility with which gases can be drawn from the regenerators through the duct 23 by the stack draft impressed on the flues. In consequence of the facts that the surfaces of duct 23 and plug 40 are substantially parallel and vertically disposed and that no obstacle intersects the stream of gases after it leaves the edge of the port, gases issuing from the port of the duct 10 of my invention, are directed into the heating flue space in a vertically directed path and without being provided with an inner turbulence or abnormal tendency to divert from stream-line flow. To the end of promoting the establishing of this condition within the gas stream, it will be observed that the upper end of the plug 40 penetrates but relatively short distance into the duct 23, so that any turbulence or eddies that may be caused by gases flowing into the void in the annular gas column created by the presence of said plug, will be overcome and corrected within the duct itself before the gases are discharged therefrom into the heating flue. The result is, therefore, that gas quantities may be regulated and discharged from the duct-port of my invention, as a vertically rising column, free of abnormal tendency to deviate therefrom as it enters the heating flue. At such times as the battery is being heated with gases of higher calorific value, this improvement is of important significance, since as hereinabove mentioned, such gases have a tendency to liberate their heat content more rapidly than preferred. When heating the battery with such gases all regenerators are operating on air, so that air flows through both conduits 17, 18 into the duct 23 and the flame flues, and the heating gas is distributed from the gas channel 31 through the nozzles 34. As a result of the fact that the gas flow regulating means of my invention tends to cause the combustion air to rise through the heating flue as a vertically rising column, it serves to inhibit an initial intimate mixing of the said air with the fuel gas issuing from the adjacent gas nozzle and, consequently, retard the combustion rate. The tendency to confine the combustion reaction to the lateral margins of the individual gaseous columns is thereby promoted, and a lengthening of the flame provided so that the inclination of fuel gases of higher calorific value to overheat the lower parts of the flues is reduced.

As hereinbefore mentioned, the fuel gases of lower heating value, as for example producer and blast furnace gases, have a relatively slow rate of flame propagation and their successful combustion and use in a structure of this type requires a preheating step prior to introduction into the heating flues. When, therefore, the battery is heated with such lean gases, one of the regenerators beneath each heating flue is reserved for preheating fuel gas and the other for preheating the combustion destined air—both gases being distributed to the regenerators in the above-described and well known manner. As shown in Figures 2 and 5, the preheated air and lean gas flow from their respective regenerators respectively through conduits 17, 18 and enter the there-with communicating flame flues through duct 23. When underfiring with lean gas, it is appreciated that in general, it is the practice to discontinue the introduction of rich gas into the flame flues and consequently the supply of that medium is cut off from the channel 31. The air and lean gas flowed through the conduits 17, 18 in preheated condition, begin to commingle at the con-

vergence of said conduits and at a point adjacent the finial of the division wall 38, shown in Figures 4 and 5, so that the combustion reaction is there initiated. Referring to these figures it will be noted that this point is at appreciable distance below the bottom of the flame flues and that consequently the preheated combustive media have actually begun to evolve heat somewhat before entering the flues. In consequence of the previously mentioned fact that gases of relatively low calorific value burn more slowly than the gases of higher calorific value, it is apparent that this feature of my improvement, i. e. a simple and effective means for inaugurating the combustion process at a point significantly below the floor level of the coking chambers makes it possible to obtain higher temperatures, at such levels, than are produced when lean gas and air are first mixed at points nearer or at the bottom of the heating flues, and the tendency, occasionally observed in oven batteries equipped for either lean or rich gas underfiring, to have so-called "cool bottoms" when they are heated with the former, is thereby diminished. The plug 40 used to restrict the flow of gas from the regenerators may be varied in diameter to alter the cross-section of the annular free space, between said plug and adjacent duct walls, so that the rate of flow of the heating media into the flame flues is capable of regulation.

An added feature of my present invention is that it provides a unique means of raising or lowering, in the battery structure, the level at which the conduits 17, 18 first converge, and therefore permits adjustment of that point, below the bottom of the heating flues, at which the preheated air and lean gas are initially allowed to mingle, and so provides means for altering the temperatures maintained at the bottom of the flues, when preheated heating gas is used for underfiring. Figures 12, 13, 14 show a duct plug means for simply effecting this objective. As will be therein noted, the plug of my invention may be provided with diametrically opposed fin-like projections 42, which are fashioned in such manner as to rest on the curved portion 43 of the finial of the division wall 38, so that when the plug is seated in the socket 39 the laterally extending fins have the effect of increasing the height of the wall section 38, thereby raising the level at which the air and heating gas are first allowed to come in contact. The general effect of this feature is to reduce, as the height of the fins is increased, the interval during which combustion is allowed to progress before the combustive gases are introduced into the heating flues. The result is a tendency to decrease the temperatures at the bottom of said flues by reducing the temperature of the gases entering them.

As clearly shown in Figure 4, the bottoms of the heating flues are raised above the oven soles. This feature has the effect of increasing the heating wall area available for absorbing the larger quantities of heat initially evolved by the combustion of rich gas and an improved distribution of such heat thereby provided. It will be further noted that the bricks 44 are beveled at a point near the heating walls to facilitate conducting heat to the bottoms of the ovens more especially during such times as the carbonization reaction is promoted by burning gases of lower calorific value.

The port plugs of my invention may be made of any satisfactorily refractory material, as for example, silica, sillimanite Al_2SiO_5 or the like,

but I prefer to use sillimanite since it can be cast or molded into objects that conform to prescribed measurements within $\frac{1}{16}$ inch. Furthermore, sillimanite plugs have the added advantage that they may be removed from the heating flues at high temperatures and suddenly chilled without danger of fracture.

An added advantage of my invention results from the fact that the juncture, between the duct plug and the seat and socket supporting it in position in the structure, is always protected from the accumulation of adventitious materials of the gas, which at the high temperatures obtaining in the battery structure, may unite with the refractory materials of the brick work and cause the plugs to freeze in the sockets. With my improvement, these gas flow regulatory means are always easily removed for exchange. For those instances where the diameter of the plug required for any duct is less than the diameter of its supporting seat, as shown in Figure 9, I bevel its lower part so that the retaining socket and supporting seat are always completely covered and protected against deposition of entrained substances of the heating gases. To assure adequate protection of the juncture between the plug and its supporting seat 50, the surface 49 of the plug is so fabricated that its circumference is slightly raised above other points of that surface, so that the contact between the plug and its supporting seat will always be established at the outer edge thereof and adventitious material be prevented from penetrating into the juncture.

To facilitate removal of the plug from the battery structure, I provide an oblong shaped hole 45 in the top of the plug and extend it lengthwise thereof to meet a transversely extending hole 46. At their intersection is the notch 47 which extends parallel with 46. A rod having a correspondingly shaped cross member at its end is inserted in 45 and in a manner to engage notch 47. The plug may be removed from its seat by the rod and removed from the battery structure through the inspection hole 36.

A further advantage provided by my invention is that the gas-flow regulating plugs are relatively smaller in cross-section than devices generally used for similar purpose, with the result that the inspection holes, at the top of the battery and through which said plugs are withdrawn from the structure, may be correspondingly reduced in cross-section and radiation losses therefrom correspondingly diminished.

In the structure incorporating my present improvement, all throttling or regulation of the flow of underfiring media to the heating flues is effected up-stream of the burning flame flues and the circuit of the gases around the heating chambers is so designed that no impedance or restriction to gas flow is created either in the flues or their communicating connections. To this end, the heating flues 19, the individual horizontal channels 28, the cross-over conduits 29 and the outlets 48 for each pair of a flue group employing the same cross-over are sufficiently large that back pressure is substantially eliminated, when gases introduced into the flues through the nozzles 34 and the air and lean gas ports 23, are burned.

Due to the tapering of the coal charge from the pusher-side to the coke-side of the battery, the amount of gas burned in the various flue groups must be progressively increased from the former to the latter named side in the interest of completing the coking process in all parts of the

charge simultaneously. The theoretical increase of gas requirement from flue to flue is of such minor magnitude that for practical purposes it suffices to graduate the ports of my invention group-wise rather than individually, with the exception of the end flues at the respective ends of the ovens.

The following table gives a preferred graduation of the combined air and lean gas ports, as shown diagrammatically in Figure 8.

Port No.	Area of port without plug	Diameter of plug	Net area of port with plug in place
101	Square inches	Inches	Square inches
	28.39	No plug	28.39
102	25.89	$2\frac{3}{8}$	21.51
103 to 106 incl.	21.51	$2\frac{3}{8}$	17.96
107 to 110 incl.	21.51	$2\frac{3}{8}$	17.08
111 to 114 incl.	19.64	$2\frac{3}{8}$	16.09
115 to 118 incl.	19.64	$2\frac{3}{8}$	15.21
119 to 122 incl.	19.64	$2\frac{3}{8}$	14.73
123 to 126 incl.	19.64	$2\frac{3}{8}$	14.22
127	19.64	$2\frac{3}{8}$	16.49
128	25.89	$2\frac{3}{8}$	21.46

In this above given table it will be also noted that the net areas of the ports leading to the end flues of each heating wall from the regenerators are of relatively greater area than those adjacent, and that such port in the end flue on the coke-side is larger than that for the end flue of the pusher-side; this is to compensate for the greater radiation from the end flues of the heating walls and doors, and for the larger quantity of coal at the battery coke-side.

As hereinbefore mentioned, the volumes of gas flowing into the heating flues of the structure embodying my herein disclosed invention are regulated at the bottoms of the heating flues, so that no throttling or dampering of such gases occurs after they have been flowed into flues. To this end, the passages 48, through which the products of combustion flow from the vertical heating flues into the horizontal channels 28, are about four times the cross-sectional area of the free-way in the air and lean gas ports at the bottom of the flues, and consequently have substantially no tendency to check the gases flowing therethrough. As a result of the fact that the gas requirements along an oven heating wall increase respectively from the pusher-side to the coke-side, it is obvious that the passages 48 on the latter side must provide unrestricted flow to larger quantities of gases than on the former, and that that effective cross-sectional passageway area which will conform to my requirements on the coke-side of the battery will be in excess of that which will be ample for said passages on the pusher-side. In the interest, therefore, of contributing as much solidity as possible to the masonry of the battery structure and avoiding conduit and passage capacities in excess of those necessary to provide the desired conditions for gas flow, I group-wise graduate the passages 48 and cross-overs 29 from one end of the ovens to the other. As shown in Figure 7, the passages 48 are graduated, as follows: the dimension "W" for all such passages is 17", excepting those passages adjacent the oven ends which are 23 $\frac{1}{4}$ "; the dimension "V" increases progressively and group-wise from the pusher-end to the coke-end as indicated in said figure; for the pusher end group of a flue pair the dimension "V" of said passage is 7 $\frac{1}{2}$ ", and

other groups comprising four heating flues successively increase in width as follows, $7\frac{1}{2}''$, $7\frac{3}{4}''$, $8\frac{1}{8}''$, $8\frac{1}{2}''$, $9''$, $9\frac{1}{2}''$, and the coke end flue group of two flues is $9\frac{1}{2}''$ wide. The cross-over flues 5 29 (Figure 1) are all about $9''$ in the dimension "A" but in the other direction "B" are graduated from the pusher-side to the coke-side in the following manner; $11\frac{1}{8}''$, $11\frac{1}{4}''$, $11\frac{1}{2}''$, $11\frac{5}{8}''$, $12\frac{1}{2}''$, $13\frac{1}{8}''$, $14''$, $14''$.

10 The invention as hereinabove set forth or exemplified, by illustrative instances, may be variously embodied and practised within the scope of the claims hereinafter made.

I claim:

15 1. In a coking retort oven battery having a series of side-by-side coking retort ovens with intermediate heating walls in which heating flues are vertically disposed, and regenerators beneath the heating walls, and conduits for flowing gases 20 from the regenerators into the heating flues of the heating walls, and ports at the upper ends of said conduits for discharging heating gases into said heating flues, flow restricting volume regulating means in said ports to restrict the flow 25 cross-area for regulating the volumes of gases flowing from the regenerators and through said ports, said flow-restricting volume regulating means terminating at their upper parts a sufficient distance below the port-mouths so as to to 30 have the throat that is formed by the volume regulating-means terminate below the port mouth of the conduit and have between the port mouth and the upper terminus of the throat an expansion chamber of larger cross-area than the cross- 35 area of the throat, so that turbulence and distortions of the gas streams created by the presence therein of the regulatory means may be rectified by a larger unrestricted portion of the ports above said means before said gases issue from the 40 mouths of the ports and the gases thus enter the heating flues without abnormal tendency to divert from a stream-line path.

2. In a coking retort oven battery having a series of side-by-side coking retort ovens with intermediate heating walls in which heating flues are vertically disposed, and regenerators beneath the heating walls, and conduits for flowing gases 45 from the regenerators into the individual heating flues of the heating walls, and ducts with fixed walls individual to the heating flues, said ducts 50 communicably connecting regenerator conduits and the heating flues, means for regulating gas flow from the regenerators through said ducts, said means comprising a core positioned at least in part within the ducts and out of contact with 55 the fixed walls thereof so as to form with the fixed walls a continuous channel extending continuously all around the core between the core and the fixed wall.

60 3. In a coking retort oven battery having a series of side-by-side coking retort ovens with intermediate heating walls in which heating flues are vertically disposed, and regenerators beneath the heating walls, and conduits for flowing gases 65 from the regenerators into the heating flues of the heating walls individually, flow-restricting volume regulating-means restricting the flow cross-area for regulating the flow of gases from the regenerators to the individual heating flues, 70 said flow-restricting volume regulating-means being removably supported inside said conduits and terminating at their upper parts a sufficient distance below the upper margins of the port mouths of the conduit so as to have the throat 75 that is formed by the volume regulating-means

terminate below the port mouth of the conduit and have between the port mouth and the upper terminus of the throat an expansion chamber of larger cross-area than the cross-area of the throat, to leave an unrestricted duct portion 5 above the regulating means for rectification of turbulence and distortion of gas that may flow through the regulated portion of the conduits, and said conduits being free of regulating means above the upper terminus of the aforesaid regulating 10 means.

4. In a coking retort oven battery having a series of side-by-side coking retort ovens with intermediate heating walls in which heating flues are vertically disposed, and regenerators 15 beneath the heating walls, and conduits for flowing gases between the regenerators and the individual heating flues of the heating walls, duct means comprising an axially disposed core providing a ring-like duct in horizontal cross-section extending continuously all around the core and adapted to regulate the volume of gases 20 flowed between the regenerator conduits and the heating flues.

5. In a coking retort oven battery having a series of side-by-side coking retort ovens with intermediate heating walls in which heating flues are vertically disposed, and regenerators beneath the heating walls, and conduits for flowing 25 gases between the regenerators into the individual heating flues of the heating walls, duct means comprising a ring-like duct continuous in horizontal cross-section with an inner core adapted to regulate the volume of gases flowed from the regenerator conduits into the heating flues, each said duct being formed as the interspace between the conduit walls and a therebetween positioned plug-like core-element of 30 lesser cross-section than the adjacent conduit walls.

6. In a coking retort oven battery having a series of side-by-side coking retort ovens with intermediate heating walls in which heating flues are vertically disposed, and regenerators beneath the heating walls, and communication 45 ways for flowing gases between the regenerators and the heating flues, duct means comprising a ring-like duct continuous in horizontal cross-section with an inner core within said communication ways adapted to regulate the gas flow 50 between said heating flues and regenerator communication ways, each such duct being formed as the interspace between the walls of the communication ways and a therebetween removably supported plug-like core-element of lesser 55 cross-section than the adjacent walls of said communication ways.

7. In a coking retort oven battery having a series of side-by-side coking retort ovens with intermediate heating walls in which heating flues 60 are vertically disposed, and regenerators beneath the heating walls so arranged that at least two regenerators are communicably connected with each of said heating flues by means of conduits extending upwards therefrom to converge in a common duct that enters the lower part of the heating flues, and division walls between those regenerators communicating with identical heating flues, said walls each terminating in a finial at the convergence of said conduits, means in the common duct adapted to adjust the gas flow between the regenerators and the individual heating flues, said means each comprising a plug-like member adapted to be removably supported on the finial of the regen- 70 75

erator division wall and extend axially into the common duct of the regenerator conduits to form the core of a continuous ring-like interspace duct within the lower part of the common duct, substantially as specified.

8. In a coking retort oven battery, in combination: a series of side-by-side coking retort ovens with intermediate heating walls containing vertically disposed heating flues; cross-regenerators, beneath the heating flues, so arranged that at least two regenerators are communicably connected with each heating flue by means of individual conduits that extend upwards from said regenerators and converge in a common duct that enters the lower part of the heating flues; division walls, between said conduits, that terminate in a finial beneath the lower part of the heating flues; supporting means on each such finial for receiving an elongated plug-like member; and plug-like members of lesser cross-sectional area than the common ducts of the regenerator conduits, and adapted for support by the finials of the conduit division walls and to extend upwards into said ducts and terminate in advance of the mouths of said ducts to form the core of lower continuous ring-like interspaces in the lower part of the common ducts between the walls of the ducts and said plug-like members, so that heating gases may be flowed therethrough from the regenerators and the heating flues.

9. In a coking retort oven battery having a series of side-by-side coking retort ovens with intermediate heating walls in which heating flues are vertically disposed, and regenerators beneath the heating walls, and ducts for flowing heating gases between the regenerators and the heating flues, elongated plug-like devices of lesser cross-sectional areas than the ducts centrally disposed therein and terminating at their upper parts below the outlets of ducts so as to form in each of the ducts a lower continuous channel extending continuously all around the plug-like device and an upper unrestricted channel immediately over the centrally disposed plug-like device.

10. In a coking retort oven battery having a series of side-by-side coking retort ovens with intermediate heating walls containing vertically disposed heating flues, and two series of regenerators beneath the heating walls, the one being adapted to preheat combustion air and the other disposed to preheat fuel gases of low calorific value, and individual conduits for flowing the preheated combustion medium from each series of regenerators into each heating flue of the heating walls, said conduits rising upwards from their respective regenerators to unite and enter the lower port of their respective heating flues through a common port so that combustion of the preheated media may be initiated before they enter the heating flues, and division walls between the preheated air and lean gas conduits terminating at the point of union of said conduits in a finial having supporting means adapted to support a gas flow adjusting device, the improvement in means for regulating the flow of gases from the regenerators and for adjusting that interval the combustion process progresses before the heating gases from the regenerators enter the heating flues, said means comprising, an elongated plug-like device of lesser horizontal cross-section than the preheated common air and gas ports of the heating flues and adapted to be removably supported on the finial of the division walls of the conduits and to extend into

said ports to form ring-like ducts, and laterally projecting fins on said means adapted to coincide with the finials of the conduit division walls to increase the height thereof, so that the mixing point of the preheated fuel gas and air may be brought nearer the bottom of the heating flues; substantially as specified.

11. In a coking retort oven battery of the combination type, in combination: elongated coking chambers alternately disposed of heating walls containing vertically disposed heating flues; regenerators beneath the heating walls communicably connected with the heating flues of the heating walls, said regenerators being disposed in two series, the one for preheating fuel gases of low calorific values and the other for preheating combustion air; means for flowing admixed preheated gas and air from the regenerators into the heating flues, said means comprising, bifurcated conduits that extend from common ports at the bottom of the heating flues to regenerators for preheating fuel gas and air; division walls, between the gas and the air regenerators and their respective conduits, that extend from the bottoms of the regenerators upwards to the points of the conduit bifurcation; and means for adjusting the gas flow into the individual heating flues and increasing the height of the division walls between the preheated gas and air conduits, said means comprising an elongated plug-like device of lesser horizontal cross-section than the common preheated gas and air ports of the heating flues and adapted to be removably supported on the finial of the division walls of the conduits and to extend into said ports to form ring-like ducts, and laterally projecting fins on said means adapted to coincide with the finials of the division walls to increase the height thereof, so that the mixing point of the preheated fuel gas and air may be brought nearer the bottom of the heating flues; substantially as specified.

12. In a coking retort oven battery as in claim 9, and in which the plug-like devices are fabricated of sillimanite, $Al(AlO_4)SiO_4$, for adjusting the gas flow into the individual heating flues and for increasing the height of the division walls between the preheated gas and air conduits.

13. In a coking retort oven battery of the combination type, in combination: elongated coking chambers alternately disposed of heating walls containing vertically disposed heating flues; regenerators beneath the heating walls communicably connected with the heating flues of the heating walls, said regenerators being disposed in two series, the one for preheating fuel gases of low calorific values and the other for preheating combustion air; means for flowing admixed preheated gas and air from the regenerators into the heating flues, said means comprising, duct means having an upper duct communicating with a lower duct continuous in horizontal cross-section with a central core adapted to regulate the volume of gases flowed between the regenerators and the heating flues, and bifurcated conduits that extend from the lower duct to the regenerators for preheating gas and air.

14. In a coking retort oven battery of the combination type, in combination: elongated coking chambers alternately disposed of heating walls containing vertically disposed heating flues; regenerators beneath the heating walls communicably connected with the heating flues of the heating walls, said regenerators being disposed in two series, the one for preheating fuel gases of

low calorific values and the other for preheating combustion air; means for flowing admixed pre-heated gas and air from the regenerators into the heating flues, said means comprising, ducts that are adapted to flow gases between the regenerators and the heating flues; and elongated plug-like devices of lesser cross-sectional areas

than the ducts and axially disposed therein to form in each duct a continuous channel with a central core, the channel extending continuously all around the plug-like device as the core between the latter and the duct wall.

5

JOSEPH VAN ACKEREN.
